UNITED STATES PATENT OFFICE.

ADOLF BOGE, OF SOLINGEN, GERMANY.

LOCK.

Application filed August 26, 1921. Serial No. 495,569.

(GRANTED UNDER THE PROVISIONS OF THE ACT OF MARCH 3, 1921, 41 STAT. L., 1313.)

To all whom it may concern:

Be it known that I, ADOLF BOGE, a citizen of the German Republic, residing at Solingen, Rhenish Prussia, Germany, have invented certain new and useful Improvements in Locks (for which I have filed application in Germany February 8, 1918, and July 18, 1919; France, July 10, 1920; Sweden, June 30, 1920; Switzerland, July 10, 1920; England, July 17, 1920), of which the following is a specification.

This invention relates to a safety door lock and the like in which the movement of the bolt is effected by a bolt-driving member that is permanently seated in the main lock and adapted to be moved through the agency of cylinder locks cooperating with it and arranged one on each side of the door.

A salient feature of the invention consists in the bolt-driving member, which is held in its intermediate position by a spring member, being provided at each of its two ends with an opening adapted to receive the end of the key, so that the latter can be thrust both from the inner and outer sides of the door through the particular cylinder lock straight into a bolt-driving member so as to effect the coupling between the rotary portion of the cylinder lock and the bolt-driving member. The bolt-driving member, which is preferably journalled in the walls of the main lock and on studs projecting from the cylinders of the cylinder locks arranged opposite to each other in the door, is equipped with teeth that mesh with teeth on the lock bolt. The two cylinder locks are preferably connected with the main locks by means of screws that pass through a slot in the bolt and serve also as guide-members for the latter, the heads of the screws being covered by a cover-plate which is locked in position in a peculiar manner so as to prevent the screws being tampered with by unauthorized persons.

By this arrangement a lock is obtained that is simple, occupies little space, is reliable in action and affords great security against opening by unauthorized persons.

One embodiment of the invention in which a mortise lock is used is illustrated in the drawing in which

Fig. 1 shows the mortise-lock by itself with cover removed, partly in elevation and partly in section,

Fig. 2 the same but with the latch drawn back,

Fig. 3 the same with the latch locked in its forward position, and

Fig. 4 shows the bolt-driving member by itself in four different views.

Fig. 5 shows an end view of the lock, partly in section,

Fig. 6 is a plan view of the entire safety lock mounted in the door,

Fig. 7 illustrates the method of preventing the removal of the fastening screws of the lock by unauthorized persons,

Fig. 8 the cover plate that renders the screws inaccessible partly dislodged.

The two cylinder locks 1, 2, each arranged on a side of the door and inserted in a hole therein, have the usual construction and are each carried by a supporting disc 3. They are held together and in place by two screws 4 arranged side by side which are passed through the inside cylinder lock, are threaded into the outside cylinder lock, and traverse the mortise-lock 5, being passed through holes in the walls 6, 7 of the latter, so that the three parts of the entire lock are secured in correct relative positions.

The head 8 of the latch is guided in the turned-up part 9 of the mortise-lock and in cut-out portions 10 of the lock-walls 6, 7, and is rigidly connected with a transverse piece 11, which is guided by means of rods 12 in guide-blocks 13 and also abuts against springs 14, which tend to hold the latch-head 8 in the position wherein it acts as latch or to press it back into this position (Figs. 1 and 6). 15 is the stem of the latch which stem by means of a slot 16 is guided on the fastening screws 3, 4 of the cylinder locks so as to be longitudinally slidable to and fro and, by means of a threaded pin 17 and a slot 18, is so connected with the latch head 8 that the latter can be moved independently of the stem 15 within certain limits and be drawn back into the lock, e. g. by means of a pressure member acting on the arm 19, independently of the cylinder locks for the purpose of operating the latch while the latch-stem 15 is locked.

The movements of the latch 8, 15, here serving simultaneously as bolt, are given by means of the cylinder locks through the intermediary, according to the invention, of the member shown by itself in Fig. 4 in va-

rious views, which member is composed of two bush-like end portions 20, 21 and of the two pin teeth 22 connecting these portions together and arranged diametrically opposite each other and is journaled in the walls 6, 7 of the mortise-lock 5. Moreover in the example the two end portions 20, 21 of said member have a hole 23 similar to a key-hole into the circular part of which extends as 10 axial stud or pin 24 on the inner cylinder 25 of each adjacent cylinder lock, so that the member can turn freely on these pins 24. The inner cylinder 25 of one or the other cylinder lock is coupled with said member, 15 so as to turn therewith, by means of the key 26 inserted into this particular lock, and, in the example, in such a way that said key engages directly into the slotted part of the hole in the member (Fig. 5, left).

20 Now the bolt-driving member by means of its two teeth 22 engages with a toothed portion of the bolt-stem 15, which portion in the example is formed by the four slit-like notches 27, 28, 29, 30, so that, by the rotation of the inner cylinder of one of the cylinder locks and of the said member coupled with it the bolt-stem 15 is pushed from the latching position (Fig. 1) into the locking position of bolt head 8 (Fig. 3) or vice 25 versa, the two pin teeth 22 of the member, in these positions corresponding to the final positions of the cylinder locks, being located one behind the other in the direction of bolt-movement, each then engaging in one of the 30 slots in the bolt-stem, as will be understood from Figs. 1 and 3. In this way the bolt-driving member also serves to secure the latch stem 15 in the two said positions, so that the provision of a separate tumbler 35 therefor is unnecessary.

40 To hold said member 20—21 safely in the said securing or locking positions, there is provided a resilient abutment, which in the example consists of a lever 33 having a spring 31 which bears against a pin 32 and presses on a flattened part 34 at the side of the member.

45 In the latching position shown in Fig. 1 the bolt stem 15 holds the latch-head 8 in its usual position, wherein it actually functions as a latch. The slot 18 in this case enables the latch-head 8 to be drawn back into the lock against the action of the springs 14 in order to open the latch closure, for example, 50 by means of a pressure device acting on the arm 19. Now when the bolt stem 15 is moved forward into the position shown in Fig. 3, the latch-head is thereby locked in that forward position in which it acts as a 55 bolt. In this position the pin 17 prevents the latch head being pressed back. Finally in order to be able to draw said head back into the lock from its Fig. 1 position by 60 means of one or the other of the cylinder locks, the slot 30 in the bolt stem is inclined

so that when the bolt-driving member is turned, owing to the co-operation of one pin of the same with the inclined part of the slot 30, the bolt stem 15 and, correspondingly with this, the latch-head 8 can be 70 drawn back farther than if the slot 30 were vertical (Fig. 2).

To prevent the fastening screws 4 from being removed by unauthorized persons, their countersunk heads are arranged in a 75 groove 40 in the face of the cylinder lock 1 that is situated on the inner side of the door as shown in Figs. 7 and 8. The sides of this groove 40 are dove-tailed, and the continuity of the lower side is interrupted as 80 shown in Fig. 7 by a part of the rotary cylinder 25 projecting into it when this cylinder is in its normal position. But when the cylinder is turned through the 180°, i. e., into the position illustrated in Fig. 8, a flat 85 portion 42 of the same registers with the groove so that no narrowing of the latter takes place and the cover plate 41 can be slipped into place. This plate has a notch 43 at the middle of its lower edge that registers 90 with the part of the cylinder that projects into the groove. Hence when the plate is pushed home and the cylinder turned into its normal position, Fig. 7, the former is secured against efforts to dislodge it. Thus the fastening screws can only be removed at the inside of the door, and even then only when the cylinder is turned by the key into the off normal position shown in Fig. 8 and the cover plate 41, after being thus unlocked, 95 is removed.

I claim:

1. A safety door lock comprising a toothed bolt; a bolt-driving member consisting of two rings with a key-opening in each and pins connecting the rings and adapted to engage with the teeth of the bolt; cylinder locks arranged at opposite sides of the door and having key-passages in line with the said key-openings, a key adapted to be inserted through any of the said key-passages into a said opening and to thus couple a cylinder lock with the bolt-driving member.

2. A safety door lock comprising a toothed bolt; a bolt-driving member consisting of two rings with a key-opening in each and pins connecting the rings and adapted to engage with the teeth of the bolt; cylinder locks arranged at opposite sides of the door and having key-passages in line with the said key-openings; a key adapted to be inserted through any of the said key-passages into a said opening and to thus couple a cylinder lock with the bolt-driving member, and a spring member for securing the bolt-driving member in its normal position.

3. A safety door lock comprising a main lock with a slotted bolt, a bolt-driving

member with key-openings at two ends, cylinder locks at opposite sides of the door with key-passages in line with the said key-openings, a key adapted to be inserted 5 through any of the said key-passages into a said opening and to thus couple a cylinder lock with the bolt-driving member, and fastening screws for commonly connecting the cylinder locks with said main lock, said 10 screws passing through the slot in the bolt of the main lock and acting as guide members for the bolt.

4. A safety door lock comprising a main lock with a bolt, a bolt-driving member with 15 key-openings at two ends, cylinder locks at opposite sides of the door with key-passages in line with the said key-openings, a key adapted to be inserted through any of the said key-passages into a said opening and to

thus couple a cylinder lock with the bolt-driving member, fastening screws for commonly connecting the cylinder locks with said main lock, said screws passing through the main lock, and means for normally rendering the said screws inaccessible, said 20 means consisting of a notched cover-plate held in a position in which it covers the heads of the said screws by the cylinder of a said cylinder lock normally projecting into the notch of the plate and being 25 adapted to release the plate only when the cylinder lock is unlocked.

In testimony whereof, I affix my signature in the presence of two witnesses.

ADOLF BOGE.
